UNITED STATES PATENT OFFICE.

WARDELL B. SHERMAN, OF ONEIDA, NEW YORK; MARION E. FOLAND AND CHARLES G. FOLAND ADMINISTRATORS OF SAID SHERMAN, DECEASED.

RAILROAD-SIGNAL.

SPECIFICATION forming part of Letters Patent No. 381,086, dated April 10, 1888.

Application filed April 11, 1887. Serial No. 234,357. (No model.)

To all whom it may concern:

Be it known that I, WARDELL B. SHERMAN, of Oneida, in the county of Madison, in the State of New York, have invented new and useful 5 Improvements in Railroad-Signals, of which the following, taken in connection with the accompanying drawings, is a full, clear, and exact description.

This invention consists in the combination, 10 with a spirally-flanged shaft pivoted at the side of the railway-track and axially parallel therewith, of certain novel devices for transmitting motion from said shaft to the signaling mechanism, as hereinafter fully described 15 and specifically set forth in the claims.

In the annexed drawings, Figure 1 is a plan view of a railroad-signaling apparatus embodying my invention. Fig. 2 is a side elevation of the same. Fig. 3 is a transverse section on 20 line $\alpha\alpha$, Fig. 1. Fig. 4 is a longitudinal section of the counter-shaft with its appurtenances. Fig. 5 is an enlarged longitudinal section of the shaft which transmits motion from the spiral to the counter-shaft, and Fig. 6 is a 25 detached side view of the clock-work.

Similar letters of reference indicate corresponding parts.

R represents one of the rails of a railroad-track, along the outer side of which and axially parallel therewith is a spirally-flanged shaft, A, pivoted at opposite ends in suitable supports, S S. Said spiral is in sufficient proximity to the top of the rail R to receive along the edge adjacent to the rail the pressure of the car-wheels passing over said rail, and the movement of said pressure from end to end of the spiral causes the same to rotate on its axis. Axially in line with the spiral A, and extending from one end thereof, is a shaft, 35 D, which is prevented from rotating, and is arranged movable longitudinally and crowded toward the spiral by means of a spring, b, pressing against the end of said shaft. On the shaft D is pivoted a pinion, C, which is provided with a clutch-face, c, adapted to engage a clutch-face, c', secured to the spiral shaft A, as best seen in Fig. 5 of the drawings.

At one side of the shaft D, and parallel therewith, is a counter-shaft, B, journaled in 40 suitable bearings secured to standards m m. To this counter-shaft are rigidly secured a

drum, H, and a ratchet-wheel, e, and on the hub of the latter is loosely mounted a gear-wheel, F, which meshes in the pinion C. By means of a pawl, f, connected with the wheel 55 F and engaging the ratchet-wheel e, motion is transmitted from the spiral shaft A to the counter-shaft B when the clutch c c' is in engagement and a car or engine moves over the rail R in the direction indicated by an arrow 60 in Fig. 1 of the drawings.

Back of the drum H is another drum, H', mounted loosely on the counter-shaft, so as to allow it to slide longitudinally thereon. It is compelled to rotate synchronously with the 65 drum H by means of a sliding coupling consisting of a pin, i, projecting from the end of the drum H and into a prolonged channel, l, in the adjacent end of the drum H', as shown in Fig. 4 of the drawings. At the rear end of 70 the drum H' the counter-shaft B is provided with a screw-threaded portion, B', on which works a nut, I, which is coupled to the drum H' by an undercut flange, n, on the nut interlocking with a flanged projection, n', on the 75 end of the drum H', as shown in Fig. 4 of the drawings.

By means of an arm, N, projecting from the nut I and sliding on the shaft D, the nut is prevented from turning, and thus said nut is 80 caused to travel longitudinally on the counter-shaft when the latter is rotated. To the shaft D are rigidly secured two shoulders, a a', between which the arm N moves during the travel of the nut I. By the collision of the 85 shaft D with the rear shoulder, a', the shaft D is crowded back in opposition to the spring b, and thus the clutch-face c of the pinion C is drawn out of engagement with the clutch-face c' of the spiral shaft A. To the supporting-standard of the rear end of the shaft D is secured a spring-catch, d, which is adapted to engage the shoulder a of the aforesaid shaft when pressed back in the manner aforesaid.

To the arm N is secured a tripper-arm, t, 95 which lies under the catch d, and in the movement of the nut I toward the spiral A said tripper-arm lifts the catch d out of engagement with the shoulder a, and thus releases the shaft D and allows the same to be pressed 100 toward the spiral, so as to cause the clutch-face c to engage the clutch-face c' by the press-

ure of the spring *b* on the rear end of said shaft.

Back of the screw-threaded portion *B'* of the counter-shaft is a spiral spring, *k*, which 5 presses on the back of the nut *I*, so as to prevent the same from losing its hold on the screw-threaded portion *B'* of the counter-shaft.

On the two drums *H* and *H'* are wound, respectively, the ropes or chains *h* and *g* in one 10 and the same direction. The rope or chain *h* passes over a pulley, *U*, mounted on an elevated support, and to the free end of said rope or chain is secured a weight, *V*, for the purpose hereinafter explained. The rope or chain 15 *g* passes over suitable guiding-sheaves, *p p*, and a drum, *O*, upon which latter it is wound and secured. The shaft of said drum is journaled in a suitable frame, *L*, on which latter is mounted a suitable clock-work, consisting, 20 chiefly, of a spur-wheel, *w*, attached to the shaft of the drum *O*. A spring-restrained bell-hammer, *j*, is arranged to be actuated by the aforesaid spur-wheel, and a bell, *M*, arranged in position to be struck by the aforesaid hammer. Another drum, *O'*, is secured 25 to the shaft of the drum *O*, and has a rope, *g'*, wound upon it in the opposite direction from the winding of the rope *g* on the drum *O*, and to the free end of the rope *g'* is attached a 30 weight, *V'*. In order to render the motion of the aforesaid clock-work more uniform, a shaft, 1, is arranged parallel with the shaft of the drum *O O'*, and has secured to it a pinion, 2, which meshes in the spur-wheel *w*. An 35 other spur-wheel, *w'*, is secured to the shaft 1 and meshes in the pinion 3, secured to a shaft, 4, which is parallel with the other shafts and has affixed to it the fan 5. Similar governing devices may be connected with the gear-wheel 40 *F*, hereinbefore described, as illustrated in Fig. 1 of the drawings, wherein 6 denotes a pinion mounted on the shaft 7, which is parallel with the counter-shaft *B*, and has rigidly secured to it the spur-wheel *F'*. The pinion 45 6, meshing in the gear-wheel *F*, transmits motion to the shaft 7. The spur-wheel *F'* meshes in the pinion 8, secured to the shaft 9, which has also secured to it the fan 10.

Inasmuch as in many cases the signal or 50 alarm is located from a fifth of a mile to a mile or more from the track-instrument or spiral *A*, and the rope *g* is required to be maintained at a uniform tension, I connect to said rope at proper intervals ropes *i'*, running oversheaves 55 *l*, and having connected to their free ends weights *v'*, as illustrated in Fig. 2 of the drawings.

The operation of my invention is as follows: 60 As a car or engine passes over the rail *R* in the direction indicated by an arrow in Fig. 1 of the drawings, the pressure of the wheels upon the edge of the spiral *A* imparts rotary motion to the same. The clutch-faces *c c'*, being 65 normally in engagement with each other, cause the pinion *C* to partake rotary motion from the spiral *A*, and the gear-wheel *F* transmits

motion from the pinion *C* to the counter-shaft *B*. During the rotation of the latter the screw-threaded portion *B'* thereof causes the nut *I* to travel toward the rear end of the shaft *B* and 70 draw with it the drum *H'*. The two drums *H H'* receiving simultaneously rotary motion, causes the two ropes *g* and *h* to be wound upon said drums, the rope *h* drawing up the weight *V*, while the rope *g* imparts rotary motion to the drum *O* and causes the rope *g'* to be wound upon the drum *O'*. As the nut *I* recedes from the screw-threaded portion *B'* of the counter-shaft *B*, the arm *N* encounters the shoulder *a'*, and thereby pushes the shaft *D* in 80 opposition to the spring *b*. The catch *d*, hooking onto the shoulder *a*, serves to retain the shaft *D* in its retracted position, and by the aforesaid movement of the shaft *D* the clutch-face *c* is thrown out of engagement with the 85 clutch-face *c'*, thus liberating the pinion *C* and allowing the counter-shaft *B*, with the drums *H H'*, to be rotated by the draft on the ropes *g* and *h* produced by the weights *V* and *V'*. During this latter motion the spur-wheel *w* of 90 the clock-work actuates the bell-hammer *j* and causes the same to strike the bell, and thus sound the alarm. During this reverse movement of the counter-shaft *B* the nut *I* is caused to travel toward the drum *H*, and by means of 95 the arm *N* and tripper *t*, connected therewith, the catch *d* is thrown out of engagement with the shoulder *a*. The shaft *D*, being thus released from the catch *d*, is then forced toward the spiral *A* by the spring *b*, and thus the 100 clutch-faces *c* and *c'* are thrown into engagement and ready again to transmit motion from the spiral *A* to the counter-shaft *B* by a car or engine passing over the rail *R* in the direction indicated by an arrow in Fig. 1 of the 105 drawings.

Having described my invention, what I claim as new, and desire to secure by Letters Patent, is—

1. The combination of a spirally-flanged 110 shaft pivoted at the side of the railway-track and axially parallel therewith, a pivoted counter-shaft, gears transmitting motion from the flanged shaft to the counter-shaft, a drum on the counter-shaft, signaling mechanism provided with actuating-drums, and a driving cord or chain connecting said drums, as set forth.

2. In combination with the spiral *A*, a pinion arranged rotatable independent of said 120 spiral, a clutch adapted to connect and disconnect said pinion and spiral, a counter-shaft, a gear on the counter-shaft engaging the pinion, a pulley or drum mounted loosely on said shaft, screw-threads on a portion of the length 125 of the counter-shaft, a nut working on said screw-threaded portion and coupled with the aforesaid pulley or drum, and an arm projecting from the nut and adapted to shift the aforesaid clutch, as and for the purpose set forth.

3. In combination with the spiral *A*, the 130 shaft *D*, movable longitudinally and provided

with the shoulders *a a'*, the pinion C, mounted loosely on said shaft, clutch-faces *c c'*, respectively, on the pinion and spiral shaft, the spring *b*, arranged to force the shaft D toward the spiral, the catch *d*, adapted to engage the shoulder *a*, the counter-shaft B, provided with the screw-threaded portion *B'*, the ratchet-wheel C, fixed to said shaft, the gear-wheel F, mounted loosely on the counter-shaft and meshing in the pinion C, the pawl *f* on said gear-wheel, the drum H, rigid on the counter-shaft, the drum *H'*, loose on said shaft, a longitudinally-sliding coupling between said drums, the nut I, working on the screw-threaded portion of the counter-shaft and coupled with the loose drum, the arm N, projecting from the nut and movably connected with the shaft D and adapted to encounter the shoulder *a'*, and the tripper *t*, connected with the arm N and adapted to trip the catch *d*, substantially as described and shown.

4. In combination with the spiral A, counter-shaft B, drum *H'*, and mechanism for transmitting motion from the spiral to the counter-shaft, signal or alarm mechanism, clock-work arranged to operate said signal or alarm mechanism, the drums O O', connected to said clock-work, the rope or chain *g*, connected at

opposite ends with the drums *H'* and O, the rope *g'*, connected to the drum O', and the weight *V'*, connected to said rope, substantially as and for the purpose set forth.

5. In combination with the spiral A, counter-shaft B, drums *H H'*, and mechanism for transmitting motion from the spiral to the counter-shaft, a signal mechanism, clock-work arranged to operate said signal mechanism, the drums O and O', connected to said clock-work, the rope or chain *g*, connected with the drums *H'* and O, the rope *g'*, connected to the drum O', the weight *V'*, attached to the free end of said rope, the pulley U, the rope or chain *h*, connected to the drum H and running over the pulley U, and the weight *V*, attached to the free end of the rope or chain *h*, substantially as described and shown.

In testimony whereof I have hereunto signed my name and affixed my seal, in the presence of two attesting witnesses, at Syracuse, in the county of Onondaga, in the State of New York, this 5th day of April, 1887.

WARDELL B. SHERMAN. [L. S.]
